CLAIM

The ornamental design of an omnidirectional remote
controller for television receivers and the like, as
shown.

DESCRIPTION

FIG. 1 is a perspective view of an omnidirectional re-
mote controller for television receivers and the like
showing our new design;

FIG. 2 is a front elevational view thereof;

FIG. 3 is a rear elevational view thereof;

FIG. 4 is a top plan view thereof;

FIG. 5 is a left side elevational view thereof;

FIG. 6 is a right side elevational view thereof; and,

FIG. 7 is a bottom plan view thereof.

Fig. 1
